UNITED STATES PATENT OFFICE.

JOHN E. ROACH, OF ST. PAUL, MINNESOTA, ASSIGNOR OF ONE-HALF TO JOHN E. GOODWILLIE, OF ST. PAUL, MINNESOTA.

CONDUIT FITTING.

Application filed March 30, 1923. Serial No. 628,775.

To all whom it may concern:

Be it known that I, JOHN E. ROACH, a citizen of the United States, residing at St. Paul, in the county of Ramsey and State of Minnesota, have invented certain new and useful Improvements in Conduit Fittings, of which the following is a specification.

This invention relates to T fittings for use in connection with conduits adapted to carry electrical conductors, and more particularly to electric fittings for use in connection with glass show cases. One of the objects of the invention is to provide an improved lamp supporting fitting of a formation which adapts it for use in the portion of a glass show case or counter to afford a clearer view of the goods on display, and be more or less concealed from view, and which is constructed to carry incandescent light bulbs extending in spaced relation lengthwise longitudinally of the counter in close proximity to the glass top and side plates of the counter.

A further object of the invention is the provision of a T-shaped body having a removable section, the removal of which will expose the entire interior of the body to render the same accessible for making wire connections between the electric conductors in the body and the lamp wires entering through the branch of the T, novel features of construction being employed whereby the making of such connections is greatly facilitated and their efficiency increased, and whereby a compact arrangement of the parts is effected.

A still further object of the invention is the provision of a device of the class described adapted to be connected into the line of a conduit and adapted to hold a lamp socket directed longitudinally of the conduit, the body of the fitting being of a configuration to extend in a conforming curve longitudinally in overlapping relation to the lamp socket, for the purpose of securing an abruptly outwardly flaring internal area in the fitting to enable the reception of the slack wire of the connections between the lamp and the conductors in the conduit. It is desirable in the art of illuminating show cases to secure the maximum angle of vision with respect to the observer so that a greater part of the display may be viewed, and to accomplish this it is essential that the conduit be small in size and that it be hung without

waste of space in the inner angle formed by the top and front glass plates of the counter, and that the branch of the T to accommodate the use of a reflector for each lamp, be of minimum length consistent with practical manufacture. To accomplish this I have formed the fitting with an indented side, which is of special form at the portion extending in longitudinal alinement with the conduit, to accommodate wrapped connections with the conductors, and which is depressed or indented in that portion adapted to accommodate the connecting wires between the lamp and the wrapped connections, the fitting being constructed to enable the lamp wires to be spread laterally, thus enabling the construction of a fitting which is appreciably smaller than an ordinary T and thereby enabling a slight increase of the angle of vision through the front and top plates of the counter, in that the outer portion of the branch of the T is extremely narrow, and of a length to bring the back of the reflector tangentially close to the top and front plates.

Other objects and advantages will be pointed out as this specification progresses, the invention consisting in the construction, combination, and arrangement of parts hereinafter described and claimed.

In the accompanying drawings forming part of this specification:

Figure 1, is a perspective view of a plurality of my improved conduit fittings shown connected longitudinally into a conduit, one lamp being shown.

Figure 2, is a fragmentary perspective view showing one fitting with the cover removed, and a second fitting partly in section.

Figure 3, is a perspective view of the cover.

Figure 4, is a transverse sectional view of the front upper corner of a glass show case, showing one form of mounting the invention; and

Figure 5, is a fragmentary top view of the fitting shown partly in section on line 5—5 of Figure 2.

In the drawings, 1 and 2 designate the glass top and front plate of a show case. The top plate ordinarily is spaced from the top edge of the front plate by the insertion of a strip of felt, not shown, thus forming a space 3 between the two plates. Extending through this space and bent downwardly

- over the outer face of the front plate is a hanger 4, formed with an inner upwardly opening hook 5 adapted to support the conduit 6. In practice, these conduits are preliminarily assembled and then placed in position in the show case, the conduits consisting of alternate pipe sections and T fittings, as shown in Figure 1 of the drawings.
- 10 The invention comprises a T-shaped body, the main portion 7 thereof being partly cylindrical and consisting in part of longitudinally spaced and aligned screw threaded pipe sockets 8, which sockets form the ends 15 of the main body portion and are adapted to have threaded engagement respectively with outwardly extending conduit sections 6 to form a continuous conduit with the main body portion. The sockets are preferably of 20 equal uniform external diameter and are integrally joined together by a partly cylindrical relatively thin wall 9, which is flush with the peripheries of the sockets and which extends around the lower half thereof (with 25 reference to Figure 2), and upwardly on either side of the longitudinal axis 9' beyond the same to a level which is situate approximately midway between said axis and the periphery of the conduits 6.
- 30 Removably fitting between the inner ends 35 of the pipe sockets and adapted to be seated on the top edge of the wall 9, is a semi-cylindrical relatively thin shell-like cover portion 10, constructed to be flush with the exterior surface of the sockets so that the 40 general shape of the main body portion will resemble a cylinder having a smooth external surface. Extending from the side of the main body portion is an extension or branch member 10'. This branch member comprises a flat wall 10'' forming the side of the fitting and which is integral with the wall 9 and extends outwardly to and beyond the longitudinal axis 11—11 of a screw threaded 45 opening 11', said axis extending in parallelism with the axis 9' of the main body member 7. From the axis 11 the wall 10'' is curved spacedly around the opening 11' to 50 assume the vertical position and extends vertically and terminates in an upper edge 12. The opening 11' perforates a vertical relatively thick wall 13, which latter is integral with the wall 10'' and is flush with the top edge 12 thereof. Opposite the wall 55 13 and parallel therewith is an inwardly curved wall 14, extending inwardly toward the main body portion to a point beyond the axis 11. On the inner side of the pipe sockets the wall 9 is divided into two extensions 9'' and 9''', said extensions being oppositely disposed and converging outwardly 60 preferably in curves, and merging respectively into the walls 13 and 14. The walls 13 and 14 extend to the level of the edge 12 65 of the walls 10'', said level being disposed in a plane represented by the line 29 (Figure 4), it here being shown parallel to a plane intersecting the axis 9' of the main body portion, and to a plane represented by the dotted line 15, in which plane is disposed 70 the axis 11. The walls 13 and 14 are each further formed, respectively, with a shoulder 13' and 14', said shoulders extending between the planes represented by the lines 29 and 15, and each being formed with an 75 upwardly and outwardly directed curve, preferably concentric with the axis 11—11 and tangent with the tops of said walls. Thus, the tops of the walls 9 and its extensions 9'' and 9''' are disposed in a plane 80 which intersects the axis of the opening 11'. The walls 13, 10'', and 14, collectively, form a relatively deep open top chamber 16, the extent of the upper portion of which is limited by the shoulders 13' and 14', but 85 the lower portion of which is in open communication with the area embraced by the walls 9, 9'', and 9''' and the inner ends of the pipe sockets 8. A threaded opening 17 in a lug carried by the wall 9'' is adapted 90 to receive a screw 18. Integral with the cover portion 10 and extending to the shoulders 13' and 14' is a flat cover section 19, having an aperture 19' which is located to register with the threaded opening 17. The 95 edges of the cover section are shaped to match the curvature of the wall extensions 9'' and 9''' to be flush with the outsides thereof.
- Integral with the cover section 19 and extending upwardly and outwardly therefrom, is a lip shaped cover plate 20, said plate being narrower at its base than the cover section 19 to form shoulders 20' at the juncture of the plate and cover section. The 100 plate is formed to fit slidably between the walls 10'', 13, and 14, and be flush with the top edges of the latter and with the shoulders 13' and 14', as indicated by the dotted line in Figure 4, whereby the closure formed 105 collectively by the parts 10, 19, and 20 is effectively prevented from bodily shifting laterally at the outer extremity of the branch member 10 (which extremity may be termed a hollow lamp supporting head), while the 110 pipe sockets 8 prevent lateral shifting of the curved portion 10 of the closure, the latter being firmly held seated on the walls 9 and its extensions 9'' and 9''' by the retaining screw 18.
- 115 Threaded in the opening is an incandescent lamp 21. The lamp is formed with a shoulder 22 adapted to engage the wall 13 (which latter extends at right angles to the main body portion 7), and with a 120 threaded nipple 23 adapted to be screwed into the opening 11' to hold the lamp firmly in longitudinal alinement with the conduit. A suitable reflector 24 is carried by the lamp, the branch 10' being of suitable length 125

to keep the reflector well up in the inner angle formed by the glass plates 1 and 2, as shown. The lamp has conducting wires 25 and 26 which have operative connection 5 with the lamp filament, not shown, said conductors being here shown (Figure 2) spliced respectively to the main conductors 27 and 28. In making these splice joints in the assembling of conduits for glass show 10 to use, the lamp must first be screwed into the opening 11', for the reason that it is directly electrically connected to the main conductors by its wires 25 and 26, as distinguished from ordinary lamps which are 15 removably held in ordinary sockets. The lamp 21 cannot be screwed into place after its wires are spliced to the mains, it being apparent that the wires would become seriously twisted. As it is important to keep 20 the parts as small and compact as possible to not obscure the goods on display, and as it is essential to have a liberal amount of slack in the lamp wire to be able to withdraw them amply from the fitting to 25 manipulate the rubber insulation and friction tape (not shown), which must be wrapped around the splice joints, ordinary T-fittings and outlet boxes are unsatisfactory. To enable handy manipulation of the parts in 30 making the joints, I have cut away all of one side of the fitting between the pipe sockets and lamp supporting head to a depth which extends an appreciable distance within the body lines of the conduit 6, but short 35 of the center of the latter. This enables the operator to freely pass his fingers under the wires in the wrapping process, and also permits the use of lamp wires of less length than would be the case if the opening in 40 the side of the fitting were on the level of the top of the pipe sockets.

By making the lamp supporting head full open at the top, it will be apparent that the lamp wires may be brought directly 45 vertically out of the hollow of the head and then be bowed inwardly in a sweeping curve to the main conductors, thus permitting the friction tape to be freely passed around the under sides thereof. The wrapped joints 50 are indicated by dotted lines in Figure 2, and are contained when the fitting is closed in the main body portion 7, the thin wall 9 and the thin cover portion 10 affording ample room between the pipe sockets for 55 their reception. When the joints are completed, the main wires are straightened out to bring the knobs formed by the wrapped joints into the main body portion. The slack lamp wires are now tucked into the shallow area afforded by the cutaway side walls, while the hollow lamp supporting head supplies ample space for so curling the wires as to avoid abrupt right angle bends, 60 as they pass into the lamp nipple 23. When the wires are properly tucked in, the cover portion 10 is initially inserted between the pipe sockets and the lip 20 is then inserted 65 between the walls 13 and 14 between which it slidably fits, thus crowding down into the cavity any protruding portions of the 70 wires. The screw 18 is then applied, whereby the closure is firmly held in place. As shown in Figure 1, any number of fittings 75 may be employed, the top sides thereof presenting a smooth appearance. By placing the lamp socket or opening 11' in offset relation to the seat of the closure, the lamp wires are brought practically to the level of the closure seat, thus affording the advantage of being easier to handle. 80

I claim:

1. In a device of the class described comprising in combination, with a lamp having a threaded nipple extending longitudinally thereof; of a T-shaped hollow body, said body including oppositely disposed longitudinally spaced and alined pipe sockets adapted to have threaded engagement respectively with conduits, a branch portion extending outwardly at right angles to the axis of said sockets and located between the latter, a screw threaded opening adapted to receive the nipple of said lamp, extending parallel with said sockets and through the wall of said branch portion and being located adjacent the outer free end thereof, a screw, the shank thereof extending into the side of the T-shaped body and having threaded engagement therewith, and a line of division, dividing the T-shaped body into two separable parts to render the interior of said body accessible, said line of division extending horizontally between said sockets at a level located adjacently above the longitudinal axes of the sockets and to a point adjacent said screw threaded nipple receiving opening, then upwardly and outwardly around the latter to the outer extremity of said branch portion, said line of division intersecting the shank of said screw. 90

2. In a fitting of the class described, comprising in combination, a pair of spaced longitudinally alined, cylindrical, oppositely disposed, open ended sockets, each adapted to have threaded engagement with a conduit to stand in longitudinal alinement therewith, a hollow head approximately equal in height to the diameter of said sockets and spaced laterally from the latter and being open at the top and inner side and having a screw threaded opening axially in parallelism with said sockets and adapted to receive a lamp, a relatively thin wall structure integrally connecting said sockets and head in a manner to form a receptacle, the interior of which is in open communication with the interior of said sockets and head, the bottom of said receptacle being in a plane which is flush with the periphery of said sockets and the bottom of said head, and the depth 100

105

110

115

120

125

130

whereof is greater than the radius of said sockets, but appreciably less than the diameter thereof, and readily removable closure means for closing and holding closed said receptacle and top of said head and the upper portion of the side thereof.

3. In a fitting of the class described, comprising in combination, a pair of spaced longitudinally aligned, cylindrical, oppositely disposed, open ended sockets, each adapted to have threaded engagement with a conduit to be in longitudinal alinement therewith a hollow head approximately equal in height to the diameter of said sockets and spaced laterally from the latter and being open at the top and inner side and having a screw threaded opening axially in parallelism with said sockets and adapted to receive a lamp, a relatively thin wall structure, including a threaded bolt hole, and integrally connecting said sockets and head in a manner to form a receptacle, the bottom of said receptacle being in a plane which is flush with the periphery of said sockets and the bottom of said head, and the depth whereof is greater than the radius of said sockets

but appreciably less than the diameter thereof, and a closure for said head and receptacle adapted to seat on the upper edge of the latter consisting of a thin shell-like cover portion of a curvature to match the periphery of said sockets and of a length to fit removably between the latter, a flat cover section integral with said cover portion and extending to said head and including a bolt hole in register with the recited threaded bolt hole, and a cover plate integral with said cover section, formed and constructed to close the side and top of said head, and be flush with the top edge thereof.

4. In a device of the class described, a cup-shaped T, coaxial pipe sockets at opposite ends of the head portion thereof, a lamp socket in the stem portion of said T, the axis of said socket being substantially parallel to the axes of the pipe sockets and in laterally spaced relation therefrom, and a removable closure for the cup-shaped T, said closure comprising a planiform central portion and an offset end portion.

In testimony whereof I affix my signature.
JOHN E. ROACH.
